UNITED STATES PATENT OFFICE.

HENRY LA ROE, OF NORTH RIVER, NEW YORK.

SEWING-TABLE.

1,182,180.

Specification of Letters Patent.

Patented May 9, 1916.

Application filed September 13, 1915. Serial No. 50,483.

To all whom it may concern:

Be it known that I, HENRY LA ROE, a citizen of the United States, residing at North River, in the county of Warren and State of New York, have invented certain new and useful Improvements in Sewing-Tables, of which the following is a specification, reference being had to the accompanying drawings.

10 This invention relates to certain new and useful improvements in tables and has for its primary object to provide a simply constructed and very convenient and serviceable sewing table in which provision is made 15 for receiving and supporting spools, thimbles, shears, pins and like articles.

The invention has for an additional object to provide a table for the above purpose having a supporting standard or pedestal 20 mounted to rotate upon a suitable base and provided with means for locking the same in various positions upon such rotation, so that the articles carried by the top of the table may be disposed in position for convenient access.

The invention has for still another object to provide a sewing table having a stationary top section and a cover or movable section, said stationary section being provided 30 with holding or retaining devices for articles generally used by dress-makers, said articles being inclosed and protected by the movable top of the table when the same is in its closed position.

35 It is an additional object of the invention to provide a sewing table having a body construction provided with means for supporting a plurality of sliding drawers or trays.

40 With the above and other objects in view, my invention consists in the novel features of construction, combination, and arrangement of parts to be hereinafter more fully described, claimed, and illustrated in the 45 accompanying drawing, in which—

Figure 1 is a side elevation of a sewing table illustrating the preferred embodiment of the invention; Fig. 2 is a top plan view of the table with the movable top or cover 50 thereof in its open position; Fig. 3 is a vertical section taken on the line 3—3, of Fig. 1; Fig. 4 is a horizontal section taken on the line 4—4, of Fig. 3, the upper drawers being removed; Fig. 5 is a detail vertical sec-

tion taken on the line 5—5, of Fig. 3; Fig. 55 6 is a detail fragmentary perspective view of the stationary section of the table top.

Referring in detail to the drawing, 5 5 designates the base upon which the table construction is supported. This base may 60 be of any desired ornamental configuration and is provided with a plurality of spaced feet 6.

7 designates the pedestal of the table which is provided in its lower end with a 65 fixed, longitudinally projecting, threaded rod 8 to extend through a central opening 9 in the base 5. A nut 10 is threaded upon the lower end of said rod to hold the pedestal in connection with said base. In the 70 lower under face of the pedestal 7, the circularly arranged series of sockets 11 are formed. To the under side of the base 5, one end of a leaf spring 12 is fixed. A vertically disposed pin 13 is loosely connected to the 75 medial portion of this spring plate by a suitable yoke indicated at 14 and said pin extends upwardly through an opening 15 formed in the base 5. A foot-actuated rod 16 is also mounted in the base 5 and has its 80 lower end loosely connected to the free end of the leaf spring 12. Normally, the spring 12 holds the upper end of the pin 13 in one of the sockets 11 provided in the lower end of the pedestal 7, thereby preventing rotation of said pedestal. When it is desired to 85 rotate the pedestal upon the base the rod 16 is depressed with the foot, so as to force the free end of the spring 12 downwardly and thus also move the pin 13 downwardly 90 in the base 5 and out of the sockets 11. After the table has been rotated to the desired position, pressure upon the rod 16 is released so that the spring 12 will act to force the pin upwardly and engage the same in another of the sockets 11.

Upon the upper end of the pedestal 7, the stationary section 17 of the table top is rigidly secured by means of bolts, screws or other analogous fastening means. Upon the 100 upper surface of this top section and in spaced relation to the perimeter thereof, the upstanding or vertical wall 18 is secured, said wall inclosing a polygonal-shaped space divided at its rear portion by means of a 105 plurality of parallel walls 19 and transversely disposed connecting walls 20 into a plurality of article receiving compartments

for the purpose of receiving pins and like articles. To the inner wall 19, a corrugated metal plate 21 is fixed which provides convenient means for receiving and supporting hair-pins. A suitable pin cushion, indicated at 22 is arranged along the inner face of one side of the wall 18. Spaced vertically disposed hooks 23 are also arranged contiguous to the wall 18 and are adapted to receive and support shears of various kinds. A bracket, indicated at 24 is also fixed upon the inner face of this wall to support a marking rule, pen knife or other article. A plurality of spaced vertical division walls 25 extend outwardly from the wall 18 and provide compartments to receive spools of thread, vertical posts or pins 26 being fixed in the section 17 of the table top to receive the spools.

27 designates a series of supporting pins which are fixed in the top section 17 at its rear portion and on opposite sides of the vertical wall 18, said pins being provided for the purpose of receiving and supporting thimbles.

25 Upon the outer face of the front portion of the wall 18, a horizontally disposed rod 28 is secured at its extremities and upon each end of this rod, one end of an arm 29 is loosely engaged. Each of these arms is 30 provided with an axle pin 30 on its free end to receive a thread spool. The arms 29 normally rest upon vertical bars or cleats 31 projecting outwardly from the wall 18. The thread spools are thus rotatably supported 35 between the cleats so that the thread may be conveniently drawn therefrom.

The movable section or cover 32 of the table top is provided with a vertical wall 33 adjacent to its edge which is adapted to rest 40 upon the outer edge of the stationary section 17 of the table top and to inclose the various article supports which are arranged upon said stationary section. This movable cover is hinged, as at 34, to the rear edge portion 45 of the stationary top section 17. While I have shown the table top as of octagonal form in plan, it will of course be apparent that the same may be constructed in various other polygonal shapes or can be of circular form, if desired.

To the under side of the body wall of the movable section or cover 32, a corrugated metal strip 35 is secured for the purpose of receiving darning or crocheting needles. 55 The front portion of the vertical wall 33 of the cover is provided with a suitable lock, indicated at 36, the latch element of which is adapted to engage with the keeper plate 37 fixed in the upper surface of the stationary top section 17. The latch bolt is actuated by means of a rotatable knob or finger piece 38.

To the pedestal 7 of the table and in spaced relation to the top section 17, two 65 pairs of horizontally disposed parallel bars

39 are secured, the ends of said bars in each pair being connected by a metal plate 40 having upstanding flanges 41 on its longitudinal edges. A metal framework 42 is secured upon the bars 39 at one side of the 70 pedestal and this framework is provided with a division wall 43. Drawers 44 are slidably mounted in the frame above and below this division wall. Relatively large drawers 45 are removably supported by the 75 respective pairs of bars 39 on each side of the table pedestal. To the bottom of each of these latter drawers, spaced cleats 46 are secured. When the drawers are placed in position, the flanges 41 of the plates 40 extend upwardly beyond these cleats and serve as guides for the drawers and prevent the lateral shifting movement of the same. Each of the drawers 44 and 45 is provided in the inner face of its front wall with a 80 suitable lock including a movable locking bolt 41' which extends downwardly through the bottom of the drawer and is adapted, when in its locking position for engagement with the outermost vertical flange 41 on the 85 plate 40. Thus the drawer is securely locked against outward movement. On the opposite side of the table pedestal with respect to the metal frame 42, a compartment 47 is constructed and is provided in its outer front 90 wall with a hinged door 48, whereby said compartment may be closed. One of the drawers 45 is divided by a plurality of parallel slats 49 into a number of compartments for the purpose of receiving patterns or like 95 articles. One end of a chain 50 is secured to the vertical wall 18 of the table top and the other end thereof is attached to the movable cover 31, said chain serving as a support for the cover when in its open position. 100

From the above description taken in connection with the accompanying drawings, it will be seen that I have provided a highly serviceable and convenient sewing table, the top of which is provided with means for 110 supporting a large number of articles, any desired one of which may be very easily and quickly removed by simply rotating the table to the desired position. The arrangement of the several parts is very compact so 115 that the table will occupy but small space. When the movable cover or section is in closed position and locked upon the body section 17 of the table top, the articles are covered and protected and liability of their 120 loss will be obviated.

While I have shown and described the preferred construction and arrangement of the several parts of the device, it is to be understood that the same is susceptible of 125 considerable modification therein and I therefore reserve the privilege of adopting all such legitimate changes as may be fairly embodied within the spirit and scope of the invention, as claimed. 120

Having thus described this invention, what I desire to claim as new and secure by Letters Patent, is:—

In a table, a flat polygonal-shaped top, a vertical wall secured upon the top in spaced relation to its marginal edge, spaced supporting bars arranged exteriorly of said vertical wall and extending outwardly therefrom toward the marginal edge of the table top, vertically swinging spool supports mounted upon said vertical wall and nor-

mally resting upon said supporting bars, and a cover hinged upon the marginal edge of the table top adapted, when in closed position, to inclose said vertical wall and 15 the swinging spool supports.

In testimony whereof I hereunto affix my signature in the presence of two witnesses.

HENRY LA ROE.
